UNITED STATES PATENT OFFICE.

JULIUS BONNER AND ISAAC EISLER, OF NEW YORK, N. Y.

EAR-RING.

SPECIFICATION forming part of Letters Patent No. 464,811, dated December 8, 1891.

Application filed May 14, 1891. Serial No. 392,763. (No model.)

To all whom it may concern:

Be it known that we, JULIUS BONNER, a citizen of the United States, and ISAAC EISLER, a subject of the King of Roumania, both residing at New York, in the county and State of New York, have invented new and useful Improvements in Ear-Rings, of which the following is a specification.

Our invention relates to certain new and useful improvements in the means employed for suspending the drop or jewel of an ear-ring, as pointed out in the following specification and claim, and illustrated in the accompanying drawings, in which—

15 Figure 1 represents a side elevation partly in section. Fig. 2 is a transverse vertical section in the plane $x x$, Fig. 1. Fig. 3 is a horizontal section in the plane $y y$, Fig. 1.

In the drawings, the letter A designates the bow. a is the arm, to which the hook b is secured, and c is the free arm of the bow, which is intended to engage the hook b. The arm a is bent nearly at right angles, and in the bent portion a' is formed a ring d. (Best seen in Fig. 3.)

20 P is the pendant, which is provided with an eye e small enough to pass freely into the ring d. After said eye has been introduced into the ring a wire screw-pivot f is passed through the ring and the eye, as shown in Figs. 2 and 3. This wire is made in the form of a screw, or otherwise so constructed that it can be readily taken out from and rein-

serted into the ring d for the purpose of removing the pendant and inserting another of 35 different form, if it is desired to do so. This change can be effected without removing the bow A from the ear. The inner surface of the eye e, carried by the pendant P, is made convex, Fig. 2, so that it bears upon the convex surface of the wire f only at one point, and the pendant is free to swing or vibrate 40 in any desired direction.

By means of the ring d, formed in the bent portion a' of the arm a, the eye e, carried by 45 the pendant, and the wire f the operation of attaching the pendant to the bow A is materially facilitated.

What I claim as new, and desire to secure by Letters Patent, is—

50 The combination, with the bow A, having the bent portion a' formed with a ring d, and a pendant having an eye e extending into the ring, of a removable and replaceable screw-pivot f, detachably extending through the 55 ring and supporting the pendant-eye, substantially as and for the purposes described.

In testimony whereof we have hereunto set our hands in the presence of two subscribing witnesses.

JULIUS BONNER.
ISAAC EISLER.
